UNITED STATES PATENT OFFICE.

JASPER BLACKBURN, OF WEBSTER GROVES, MISSOURI.

HINGED GUY-CLAMP.

1,252,540.

Specification of Letters Patent.

Patented Jan. 8, 1918.

Application filed November 15, 1915. Serial No. 61,711.

To all whom it may concern:

Be it known that I, JASPER BLACKBURN, a citizen of the United States, and resident of Webster Groves, Missouri, have invented 5 certain new and useful Improvements in Hinged Guy-Clamps, of which the following is a specification containing a full, clear, and exact description, reference being had to the accompanying drawings, forming a part 10 hereof.

My invention relates to improvements in hinged guy clamps wherein a plate, arranged to be secured to a pole is provided with bearings in which, to pivotally or hingedly support a guy clamping means comprising a tapering socket and wedge.

The object of my invention is to construct a simple inexpensive and easily operated guy clamp which may automatically adapt itself 20 to different arrangements of guys; and to arrange a guy clamp comprising a tapering socket and wedge, wherein an efficient, and easily operated means is employed for holding the wedge in different positions relative 25 to the socket.

With the above object in view, my invention consists in certain novel details of construction and arrangement of parts as hereinafter fully described, pointed out in my 30 claims and illustrated by the accompanying drawings, in which—

Figure 1 is a side elevation of a device embodying my invention, a fragment only of a pole being shown;

Fig. 2 is a front or face view of the device;

Fig. 3 is a longitudinal sectional elevation of the device taken through the approximate center thereof;

Fig. 4 is a transverse sectional plan of the device taken through the approximate center thereof;

Fig. 5 is an end view of the socket alone;

Fig. 6 is a vertical sectional elevation of 45 the socket;

Fig. 7 is an end view of the wedge alone;

Fig. 8 is a side elevation of the wedge;

Fig. 9 is a plan of the wedge;

Fig. 10 is a vertical sectional elevation of 50 the socket and wedge with a section of guy therein showing the wedge held against inward movement relative to the socket, to permit movement of the guy over the wedge;

Fig. 11 is a sectional plan of the socket 55 and wedge showing a tap screw in position

to hold the wedge against movement inwardly relative to the socket, and

Fig. 12 is an elevation on a reduced scale showing the whole structure of my invention employed as a guy clamp, and the 60 plate of my invention as used for supporting a guy to prevent splitting of a wooden pole.

Referring by numerals to the accompanying drawings, 15 designates a plate of substantially rectangular formation, and whose cross section is arcuate to conform to a pole, and which plate has on its rearmost face spurs 16 to assist in the holding of the plate in position on a pole and through which 70 plate there is formed openings 17 for the further or permanent securing of the plate to the pole by use of lag screws, spikes, or the like.

Formed through the center portion of this 75 plate there is an aperture 18 through which a guy is to be passed. Outstanding from the plate and on each side of the aperture 18 there is formed a bearing 19 and outstanding from the plate above the aperture 80 18 is a channeled guy supporting lug 20.

The numeral 21 designates a socket which tapers from end to end, is formed hollow throughout and in cross section is substantially oblong with parallel sides and rounded 85 ends. On each side of the socket and extended beyond the body thereof is an integral trunnion 22 which is arranged to seat in the bearing 19 of the plate to permit of a pivotal or hinged movement of the socket 90 relative to the plate.

In the one side wall of the socket there is a way 23 which opens to the interior of the socket and parallels the median line thereof. In this way 23 adjacent the larger 95 end of the socket there are the shoulders 24.

In the opposite wall of the socket arranged along the median line thereof is one or more tapped openings 25 arranged to receive a set screw 26 for the purpose of holding the wedge block 27 with its feather 28 seated in the way 23 and with its shoulders 29 against the shoulders 24 of said way whereby to hold the wedge outwardly relative to the socket 21 as clearly shown in 100 Figs. 10 and 11, to permit easy movement of the guy around said wedge and through said socket. In the wall of the socket, having the way 23, there is a tapped opening 30 intersecting said way for the purpose of re- 110

ceiving the tap screw 26 whereby the tap screw may be employed to move the wedge to free its feather from said way and permit the wedge to be drawn by the guy into said socket to clamping position.

The device of my invention is designed primarily for use in connection with guys extended through openings formed in wooden poles and in view of the fact that different arrangements of guys necessitate the forming of said openings through the poles at different angles such for instance as horizontally through the poles as shown in Fig. 3, or diagonally through a pole as shown in Fig. 12.

I have found it advantageous to hingedly or pivotally support the guy clamping means so that the clamping means may be held in substantial alinement with the guy, which arrangement obviates angles or bights in the guy offering resistance to the movement of the guy through the clamping means in adjusting the guy as well as obviating angles tending to break the wire or at least mar its protecting surface such as galvanizing.

Having thus described my invention what I claim as new therein and desire to secure by Letters-Patent of the United States therefor is:—

1. In a device of the class described, a tapering socket having openings through opposite walls thereof, an axial way formed in one of said walls, and an offset shoulder in said way, a wedge having less thickness than the distance between said opposed walls

of the socket and a feather having an offset shoulder arranged to coöperate with said way and shoulder for holding the wedge against movement relative to the socket.

2. In a device of the class described, a tapering socket having tapped openings in its opposite walls, a way in one of said walls intersecting said tapped opening and a shoulder in said way, a wedge for insertion in said socket, a shouldered feather on said wedge, and a screw arranged to be inserted in one or the other of said tapped openings to engage the wedge to either hold its feather and shoulder seated in the way and against the shoulder of the wall of said socket or to engage the wedge to release the feather and shoulder from the way and shoulder of the socket for the purposes stated.

3. In a device of the class described, a plate, having an opening therethrough and a bearing on each side of said opening, a tapering socket, having trunnions for mounting in said bearings whereby the socket may be oscillated relative to the plate and a wedge arranged to secure a cable in said socket, substantially as shown and for the purposes stated.

In testimony whereof I have signed my name to this specification in presence of two subscribing witnesses.

JASPER BLACKBURN.
